(57) **CLAIM**

The ornamental design for a spoon, as shown.

DESCRIPTION

The claimed spoon is a utensil consisting of a small, shallow bowl on a handle, used in preparing, serving, or eating food. FIG. 1 is a front elevational view of a spoon showing my new design;

FIG. 2 is a rear elevational view thereof;

FIG. 3 is a top plan view thereof;

FIG. 4 is a bottom plan view thereof;

FIG. 5 is a perspective view thereof;

FIG. 6 is a cross-sectional view as taken along line 6—6 of FIG. 1;

FIG. 7 is a cross-sectional view as taken along line 7—7 of FIG. 1; and,

FIG. 8 is a cross-sectional view as taken along line 8—8 of FIG. 1.

1 Claim, 2 Drawing Sheets

FIG. 5

FIG. 6

FIG. 7

FIG. 8
